UNITED STATES PATENT OFFICE.

MADISON WILSON GAILLARD, OF MOBILE, ALABAMA.

AUTOMATIC CHISEL HAMMER.

Application filed August 6, 1926. Serial No. 127,711.

The present invention relates to improvements in automatic chisel-hammer and has for an object to provide an improved instrument for dental and other uses in which a 5 reciprocating hammer action is produced for the purpose of chipping away enamel, plugging teeth, chipping rust from ships, etc.

Another object of the invention lies in providing an improved tool of the character above described in which the hammer action is direct and automatic and in which the parts are simple, few and easily accessible and in which the entire instrument is compact, light and easily handled.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a plan view of an improved instrument constructed according to the 25 present invention.

Figure 2 is a side view thereof.

Figure 3 is a section taken on an enlarged scale along the line 3—3 in Figure 1 with a portion of the handle broken away.

Figure 4 is a vertical section taken on the line 4—4 in Figure 3, and

Figure 5 is a horizontal section taken on the line 5—5 in Figure 3.

Referring more particularly to the drawings 35 6 designates the handle of the tool which may conform to any shape desired and through which passes the rotary shaft 7 adapted to have connection with a dental engine or other source of power by which the shaft may be continuously rotated.

The end of the shaft projects beyond the end of the handle 6 where it carries the cam 8 affixed thereto. This cam is adapted to occupy a recess 9 made through the side wall 45 of a weighted plunger or hammer 10 having the cylindrical or other desired form and fitted to reciprocate in the cylindrical or other casing 11, the axis of which preferably extends at substantially right angles to the axis of the handle and shaft 7. The cam 8 is intended to cooperate with the upper wall of the recess 9, which is of complementary cam form having the inclined wall 12 extending from one edge downwardly toward the central part of the recess 55 and resulting in the high cam point 13 adja-

cent which is the abrupt shoulder 14 joining the high cam point with the upwardly offset curved wall 15.

The casing 11 is provided with the lateral 60 nipple or branch 16 internally threaded as indicated at 17 to screw upon the externally threaded reduced part of the handle 6. The handle is provided with a shoulder 18 adjoining the threaded reduced part against 65 which the nipple 16 is adapted to abut. The casing 11 is threaded externally at its upper end, as indicated at 19 to receive the internally threaded and flanged cap 20, which houses and adjusts the coil spring 21 fitted 70 in the upper end of the casing and within the socket 22, which opens downwardly through the top portion of the hammer plunger 10.

At the lower end of the casing screw 75 threads 23 are provided to receive the internally threaded flange of the lower cap 24, which is provided with a central opening about which extends the depending flange 25 to receive and act as a guide for the stem 80 26 of the tool holder, which is composed of said stem and a head piece 27 of greater diameter than the stem whereby the tool holder may be prevented from disengagement from the lower cap 24.

As shown in Figures 3 and 5 the head or cap piece 27 is provided with peripheral notches 28 and a pin 29 is adapted to occupy a selected notch, this pin being driven through an opening made in the lower 85 cap 24.

The stem 26 of the tool holder is provided with the threaded socket to receive the threaded shank 30 of the chisel, hammer or other tool 31.

In the operation of the invention, the shaft 7 is continuously rotated by hand, dental engine, or other appropriate source of power. The rotating cam 8 wiping down the inclined wall 12 will raise the hammer plunger 10 when the high point of the cam 8 is beneath the high point 13 of the cam wall. The spring 21 will be compressed, so that when the high point of the cam 8 moves past the high point of the cam 13 and opposite the abrupt shoulder 14, the plunger is released and will descend by gravity and forcibly by the action of the previously compressed coil spring 21. The lower end of the hammer or plunger is designed to strike the head piece 27 of the tool holder, it being understood that by pressing the tool 110 31

against the tooth or other object, the tool holder has been shifted inwardly of the casting to the desired extent, whereby, on descent of the plunger, the head piece 27 will be struck urging the tool against the tooth for the desired purpose.

In the drawings I have shown for convenience of illustration a chisel and this chisel and the plunger are normally held against rotary movement but by removing the pin 29 the chisel may be turned. The chisel is beveled and in one position it may cut, say, on the right side of the cavity. By adjusting it a quarter turn such as is permissible by the arrangement of the notches 28 and pin 29, it may cut back of the tooth. Another quarter turn of the tool holder and the chisel may cut upon the left side of the cavity and by giving it a further quarter turn the same will cut only in front of the cavity. In other words one chisel can be used in cutting any portion of the tooth, obviating the requirement for frequently changing instruments.

The adjustment referred to can be made quickly and expeditiously by simply unscrewing the lower flange cap 24. This also gives access to the bottom of the casing and to the bottom of the hammer. The upper cap 20 permits of the adjustment of the tension upon the coil spring 21, so that the force of the blow can be governed nicely. This removable upper cap 20 also gives access to the upper end of the plunger and casing. The lateral nipple 16 may be readily unscrewed from the handle 6 thus separating both handle and casing and the casing forms a unitary construction carrying all of the parts with the exception of the cam and it enables the cam and the other parts to be readily separated.

The device will eliminate heat from friction on the tooth, most pain to the patient, and the buzzing noise so disagreeable to the patient. The device will also save the dentist time. It is noted that the cam lifts at the center of the long axis of the hammer and the lifting action is therefore a direct one. The device may be also used for heavy mechanical work, such as chipping rust from ships, etc.

It is obvious that various changes and modifications may be made in the details of construction and design of the above specifi-

cally described embodiment of this invention without departing from the spirit thereof, such changes and modifications being restricted only by the scope of the following claims:—

What is claimed is:—

1. An instrument as described comprising a handle, a rotary shaft therein, a cam on the end of the shaft, a casing removably connected with the handle, a hammer in the casing having a lateral recess for receiving the cam, said recess having an upper cam wall for cooperating with said rotary cam, a coil spring for urging the plunger in one direction, a removable cap for the casing for adjusting the tension of said coil spring, a removable cap on the other end of said casing having a guide flange, and a tool holder having a shank sliding through said guide flange and provided with a peripherally notched enlarged head piece in said last mentioned cap for engagement by said hammer, and means carried by said last mentioned cap for engaging the notches in said head piece for adjusting the tool holder about its axis.

2. A tool as described comprising a handle, a shaft mounted for rotation in the handle, a cam on the inner end of the shaft beyond the handle, a casing removably connected to the inner end of the handle and into which said cam projects, a hammer in the casing of piston form mounted for longitudinal movement in the casing in a direction at right angles to the handle and shaft, said hammer having intermediate its ends a lateral opening to receive said cam and having the inner wall of the opening constructed to provide a cam shoulder against which said cam is adapted to operate and said cam having an abrupt shoulder for releasing the cam shoulder of the hammer, a spring in the casing engaging the inner end of the hammer, a tool holder carried at the outer end of the casing to receive impact from said hammer and adapted to carry a tool, and adjustable means mounted on the inner end of the casing for closing the same and maintaining the hammer in position, said adjusting means adapted to engage the spring and vary the tension of the same against said hammer to regulate the force of impact of the hammer against the tool holder.

MADISON WILSON GAILLARD.
